United States Patent Office.

JOHN FANNING, OF BROOKLYN, NEW YORK, ASSIGNOR TO THOMAS OTIS LE ROY AND COMPANY, OF NEW YORK CITY.

Letters Patent No. 91,426, dated June 15, 1869.

IMPROVEMENT IN MOULD FOR CASTING SOLDER.

The Schedule referred to in these Letters Patent and making part of the same.

To all whom it may concern:

Be it known that I, JOHN FANNING, of Brooklyn, in the county of Kings, and State of New York, have invented and made a certain new and useful Improvement in Moulds for Casting Solder and other metal into bars or pigs; and I do hereby declare the following to be a full, clear, and exact description of the said invention, reference being had to the annexed drawing, making part of this specification, wherein—

Figure 1 is a plan of said mould, complete;

Figure 2 is a cross-section of the same; and

Figure 3 is an end view, with the end-piece of the mould turned up, to give access to said mould.

Similar marks of reference denote the same parts.

In making moulds in which solder and other metals are usually cast into bars, ingots, or pigs, it is usual to engrave or otherwise form names, letters, numbers, or other characters in the bottom of the mould, whereby the article cast is designated, or its quality made known, and the maker's name also denoted.

These moulds are very costly, and it is difficult to make the characters clear and handsome at the bottom of a mould, because of the depth of the same. Besides this, the characters being a part of the mould, necessitates the construction of a complete mould for any change of character, to designate a different quality of metal, although the bar or ingot may be the same size and shape.

The present invention consists in a sliding plate, forming a movable bottom to the mould, and in this the letters or characters are formed.

This facilitates the construction of the mould, by enabling the workman to engrave or form the letters much more easily than can be done at the bottom of the mould, and the plates being movable, the mould itself may be employed with different plates, thus saving cost in the original construction of the mould, and

rendering it more useful, and lessening the number of moulds required.

In the drawing the mould is shown as made with a bottom portion, *a*, upon which are longitudinal bars *b c d*, and end portions *e f*, so as to produce two cavities, or moulds, for receiving the melted lead or other metal.

These moulds may be of any desired size or shape, and grouped together in greater or less numbers.

The end-piece *f* is made movable, and the mould is formed with dovetailed, or under-cut grooves, at the junction of the bottom and sides of the mould, so as to receive the movable bottom plate *h*, that is slipped endwise into the said grooves, and contains, in or upon its upper surface, the letters or characters that are to be produced in the bar, ingot, or pig, that is cast in said mould.

The end-piece *f* being movable, gives access for removing one of the plates, *h*, and introducing a different plate, as occasion may require.

I do not claim casting stereotype plates between a matrix and a dovetailed wooden block, as this has before been done.

What I claim, and desire to secure by Letters Patent, is—

Forming the bottom of the mould with a recess, for receiving the movable bottom, that is slipped into place as set forth, and contains the letters or characters to be formed in casting upon the ingot or bar, substantially as set forth.

In witness whereof, I have hereunto set my signature, this 13th day of April, A. D. 1869.

JOHN FANNING.
